UNITED STATES PATENT OFFICE

2,054,396

MOBILE TOY CAROUSEL

Clarence A. Sumwalt, Texhoma, Okla.

Application December 10, 1935, Serial No. 53,799

7 Claims. (Cl. 272—29)

This invention relates to a unique child's toy which is especially adapted for use by little girls and has more specific reference to a wheel supported vehicle of a walking attendant steered type expressly constructed to function either as a 5 carousel or so-called merry-go-round, the same being designed to accommodate dolls or the like.

Without attempting to give a résumé of the state of the art to which the invention pertains, 10 I would say that I am aware that movable and portable toys of somewhat general merry-go-round types have been patented. Under the circumstances, in perfecting the ideals of my own developments and conceptions I have perfected 15 what I believe to be a novel contribution to this line of endeavor in that it is characterized by a handle-equipped wheel-supported platform constituting a carriage for a unique turn-table, which turn-table serves as a rotor for carrying doll accommodation seats as well as an ornamental 20 detachable overhead canopy or umbrella.

Structurally speaking, one feature of the arrangement is dedicated to the particular construction of the turn-table and the special fixture 25 means with which it is provided to render it susceptible of accommodating the two-way doll chairs or seats as well as the companion selectively usable canopy.

A further feature of construction has to do 30 with the particular developments of the two-way or double-type seat for dolls or other toys, said seats being bodily detachable, interchangeable and so made as to allow the dolls to face the direction of rotation according to the direction of 35 movement of the vehicle as a unit.

An additional development has to do with the particular construction and arrangement of the clutch-type gearing and novel pulley and belt arrangement believed to be indispensable in a 40 device of this type to promote satisfactory driving of the turn-table from one of the vehicle wheels.

In addition to this, there is the canopy unit 45 and its special adapter means designed for effective cooperation with existing brace means forming a part of the turn-table assemblage.

Other features and advantages will become 50 more readily apparent from the following description and drawings.

In the drawings:

Figure 1 is a side view of the complete toy as developed in accordance with my present ideals and personal conceptions.

Figure 2 is a top plan view depicting in par-

ticular the underneath details of the platform structure.

Figure 3 is a top plan view of the platform showing the rotary turn-table with the canopy removed to illustrate the structural arrangement 5 with requisite particularity.

Figure 4 is a perspective view of one of the details.

Figure 5 is a section taken approximately on the plane of the line 5—5 of Figure 2. 10

Figures 6 and 7 are detail views of the attaching means for the ornamental umbrella or canopy arrangement.

Figure 8 is a fragmentary view showing the belt driven pulley assemblage. 15

Figures 9 and 10 are detail sections on the lines 9—9 and 10—10 respectively of Figure 1.

As a matter of convenience of introduction to the detailed description, I call attention first to Figure 5. Taking this into consideration with the other figures it will be observed that the numeral 11 designates a suitable platform constituting a part of the vehicle, and that attached to this, by suitable hangers 12, are the stub axle portions 13 of the wheels 14 and 15. I distinguish these 20 wheels merely because the wheel 15 serves as the driving means for the turn-table arrangement whereas the wheel 14 is merely a free idling member. I might say in this connection that the axle 13 of the wheel 15 is provided with a beveled gear 16 for power transmission purposes. At the front 25 of the platform, as shown in Figure 1, is a suitably swivelled caster or steering wheel 17. Also at this point is an appropriate handle 18 and this is attached to the platform by any convenient 30 or practicable yoke and hinge means. The numerals 19 merely designate bracing blocks on the underside of the platform board while the numeral 20 designates a central depending stabilizing bearing or device. This is located beneath a suitable bushing or bearing 21 mounted in the central portion of the platform to accommodate the vertical stabilizing pin or shaft 22. This shaft serves as a guide and retention 35 member for the rotary turn-table 23 and its associated appurtenances. Incidentally, the pin 22 need not necessarily be turnable since it is more in the nature of a guide member. The turn-table 40 23 is in the form of a circular block of wood whose periphery is grooved so that it functions as a power take-off pulley for the rubber propulsion belt 24. This belt cooperates with an adjacent or complementary smaller pulley 25. The pulley 25 is mounted on the driven vertical shaft 26 operable in and out in a guide slot 27. The driven shaft 50

55

has a bevel pinion 28 in driving mesh with the bevel gear 16. In connection with this arrangement, I call attention to the numeral 29 which designates a carrier arm, this being attached at one end to the pulley and pivotally anchored at the top of the platform as shown in Figure 8. Then on the underside there is a similar companion arm 30 pivoted intermediate its ends as indicated at 31. This is operable in a guide bracket 32 and is controlled by a manually regulated push-pull lever 33. Considering the same arrangement, one might consider the arm 29 merely as an equalizer or stabilizer and might consider the part 30 as the lever pivotally attached to the platform and operatively joined with the pinion 28 so as to swing the pinion toward and from the gear 16 to provide the desired clutch action. That is to say, this arrangement permits the clutch arrangement to be provided to render the turn-table 23 operable at the discretion of the walking attendant. Under these circumstances, we might well call the wire member 33 a controlling handle. It is properly shaped to include a finger piece or grip 34 and is cooperable with a keeper bracket 35. In addition it has a laterally bent keeper finger 36. This finger can be engaged on either side of the keeper bracket 34 to hold the parts in predetermined adjusted relationship. With the rubber traction belt 24 and slot arrangement 27, the belt normally pulls the pulley equipped clutch unit in a direction to disengage it from the gear 16. Thus in order to retain the parts engaged the handle or wire 33 must be positioned so that the keeper finger 36 is suitably engaged with the retaining bracket.

Attention now comes to the carrier unit which is more or less in the nature of a spider. This includes a central plate portion 37 fastened to the turn-table and equipped with upstanding radial arms 38 terminating in horizontal adapter fingers 39, releasably engageable with retaining clips 40 carried by the chair portion 41 of the detachable doll chairs or seats 42. Before describing the specific seat construction I call attention to the numeral 43 in Figure 5 which designates a hub member to fit over the upstanding end portion of the hub pin 22. This prevents rocking of the turn-table, that is, keeps it in a more or less horizontal plane and in proper spaced parallelism with respect to the platform 11. I might also call attention at this time to the intersecting brace wires 44 which serve to stabilize the light-weight sheet metal arms 38. These wires also serve to accommodate the attaching fixture 45 of the canopy or umbrella 46. This umbrella comprises a standard 47 and canopy properly constructed and ornamented for fancy appearance. At its lower end the standard is provided with downwardly and outwardly diverging members 48 attached to radial channel elements 49. These elements as shown in Figure 7 form a sort of a cruciform holder and they are releasably engageable with the brace wires 44 allowing the brace wires to have the additional function of adapter means for the cruciform holder. Thus the canopy as a unit can be applied and removed according to the discretion of the user. A suitable protective housing or guard 50 is provided to conceal the turn-table or pulley assemblage as indicated in Figure 5.

Referring now to the chair construction, I would point out that this is of a double or duplex type. That is to say, the central portion formed at the seat proper while the depending stirrups 51 at the ends provide selectively usable foot rests

for the dolls (not shown). The numeral 52 designates a back plate which is hingedly attached by arms 53 to the spaced parallel side walls of the chair proper. This allows the backing plate to swing over from the position shown in Figure 10 to the opposite side and provide a unique convertible chair or seat.

By way of summation, novelty is thought to reside in the provision of a wheel supported platform 11 having a properly stabilized and balanced pulley 23 which functions essentially as the turn-table, this being driven by clutch equipped gearing means between itself and one of the wheels, that is the wheel 15. Under the circumstances by pushing the vehicle along the ground in an obvious manner the turn-table including the chairs and other details is set into rotation so as to provide the desired portable merry-go-round arrangement. More explicitly, novelty is predicated upon the manually regulated gear driven clutch means, susceptible of being rendered operative or temporarily inoperative at the discretion of the user. In addition to this, I call attention to the sheet metal fixture which is attached to the turn-table and constitutes a rack or carriage for the bodily detachable and interchangeable chairs or devices 42. I am also concerned with the brace arrangement 44 wherein this has the additional function of holding means for the cruciform channels 49 on the base portion of the canopy structure. All of the parts have been carefully selected and coordinated to provide their proportionate share in the development of a unique merry-go-round doll carriage or vehicle.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is claimed as new is:

1. As a new article of manufacture and as a component part of a toy carousal of the class described, a doll seat for use on a merry-go-round comprising a sheet metal unit constructed to define a central channel-shaped doll seating member, having duplicate depending step-like end members, said end members constituting foot rests selectively usable, a vertical back-plate swingable into either of said foot rests, and arms pivotally attaching the intermediate portion of the back plate to the intermediate portions of the side wall of the seating member.

2. In a toy carousal and doll vehicle of the class described, a wheel supported platform, and a wheel driven merry-go-round carried by said platform and including a turn-table, a spider attached to said turn-table and embodying upstanding radial arms terminating in horizontal adapters and attaching devices for removable doll chairs; a vertical pin carried by said platform and extending above the platform; said turn-table being rotatable on said pin and said spider including a tubular hub-member rotatably surrounding the adjacent end of the pin.

3. In a structural assemblage of the class described, a wheel supported platform, a merry-go-round mounted for rotation on said platform; an operating connection between the merry-go-

round and one of said wheels, said merry-go-round including a spider embodying radial arms and a cruciform brace unit for said arms, and a canopy including an umbrella, a standard and 5 a cruciform attaching member for the standard having intersecting channel members releasably engageable with the cruciform brace unit.

4. A doll toy of the class described comprising a wheel supported platform, a concentrically disposed fixedly mounted spindle attached to and 10 rising from said platform, a turntable including a marginal grooved disk-pulley attached to said spindle above said platform, a carrier unit including a central hub portion superimposed upon 15 and directly attached to said pulley and having upstanding radial arms terminating in horizontal doll chair adapter elements, brace members for said arms attached thereto, said platform having an eccentric arcuate slot, a driven shaft 20 mounted for sliding and rotation in said slot, a relatively small power-propulsion pulley carried by said shaft, a flexible belt trained over said pulleys, said shaft being provided with a pinion, one of the supporting wheels being provided with a driving gear enmeshed with said 25 pinion, and a pivotally mounted operating lever attached to the platform and connecting with said shaft to adjust the pinion toward and from the driving gear.

5. In a toy doll carousal of the class described, a wheel supported platform provided with driving and driven shafts operatively joined together, a turntable mounted for rotation on said platform, and operatively connected with said driven 30 shaft, a spider unit having a central hub portion attached to the turntable and including upstanding outwardly diverging arms terminating

in horizontal chair adapted elements, a criss-cross brace attached to the spider arms and located in spaced parallelism above the platform, and a canopy including a standard having downwardly diverging arms and a cruciform base with 5 which the arms connect, the elements forming said base being of channel-shaped cross-sectional form and releasably engaged with the members of said criss-cross brace.

6. As a component part of a structural assembly of the class described, a marginally grooved disk constituting a combined pulley and turntable, a unitary one-piece spider structure having a centralized plate portion superimposed on and directly attached to said turn-table and 15 provided with marginal radially disposed upstanding diverging arms, the free ends of said arms terminating in horizontal adapter elements to accommodate interchangeable and detachable doll chairs, and a substantially cruciform brace 20 having the ends of its arm portions attached to the spider arms in the manner and for the purposes described.

7. As a unitary structural and component part of a mobile toy carousal of the class described, a 25 detachable canopy unit including an umbrella, a vertically disposed central supporting stem for the umbrella having base means at the lower end thereof, said base means embodying a horizontally disposed cruciform member, the parts 30 of which are disposed in intersecting relationship and are channel-shaped in cross-sectional form, and further including inclined brace members secured to the outer ends of the channel-shaped arms and attached at their inner ends to the 35 intermediate portion of said stem.

CLARENCE A. SUMWALT.
